METHOD OF AND APPARATUS FOR WINDING
AND UNWINDING MATERIALS FOR DYE-
ING AND FOR OTHER PURPOSES

Bertram J. Goldsmith, Neshanic, N. J.

Application November 29, 1938, Serial No. 242,904

8 Claims. (Cl. 8—151)

This invention relates to an apparatus for and a method of dyeing fabrics and is applicable also and more broadly generally to the treatment of fabrics and other materials which are ordinarily wound in a roll and are required to be unwound, usually for the purpose of subjecting such materials to the action of a fluid.

One object of the invention is to provide an improved apparatus for and a method of dyeing fabrics, the method being such that the apparatus preferably utilized for performing the method takes up a relatively small space. Another advantage of the present method and apparatus results from the relatively low tension on the fabric in the unwinding thereof from the roll as successive portions of the fabric are brought into contact with the dye liquid.

Another object of the invention is to provide an efficient apparatus for performing the method, the apparatus being operative to automatically unwind the fabric from its original roll and to re-wind the same on the core or drum of said roll.

A further object of the invention is generally to provide an improved method of unwinding fabrics or other materials from a roll for subjecting successive portions of the fabric to the action of a dyeing liquid or other liquid or fluid.

The above objects and advantages of the invention and other advantages thereof will be more fully understood from the following description considered with reference to the accompanying drawings illustrating the preferred embodiment of the invention.

In the drawings:

Fig. 1 is a side view of an apparatus embodying the present invention and utilized for performing the method thereof;

Fig. 2 is an end view, in elevation, of the apparatus;

Fig. 3 is a sectional view on the line 2—2 of Fig. 1;

Figs. 4 to 9, inclusive, are views illustrating more or less diagrammatically the several steps in the method.

Referring now to the drawings in detail, the method of the present invention will be described first and thereafter the presently preferred form of the apparatus utilized for performing the method will be described.

Accordingly, referring to Fig. 2 and Figs. 4 to 9, inclusive, a roll R of fabric or other material including a core or drum 10 about which the material is wound, is shown mounted for rotation within a rotary outer drum 12 containing the dye liquid L. The inner end of the fabric wind-

ing is secured to the periphery of the inner drum or core 10 of the roll as indicated at 14. The outer end portion 16 of the roll of material is unattached, whereby the roll is free to unwind when the roll is rotated.

At the start of the operation the outer end portion 16 of the fabric winding hangs freely as illustrated in dotted lines in Fig. 2, but upon rotation of drum 10, said fabric portion 16 is impelled by centrifugal force toward the inner surface of 10 the outer drum 12, and is thereby caused to project through the liquid L contained in drum 12 into engagement with said inner surface of the outer drum. Said inner and outer drums 10 and 12, respectively, are then rotated simultaneously 15 in the same direction but at different speeds of rotation. Assuming that the material was wound on the inner drum 10 by rotating said drum 16 in a counter-clockwise direction, then in performing the method the drums are rotated in a 20 counter-clockwise direction as indicated by the arrows in several figures of the drawings. Starting with the condition of the material in which it is mounted on the inner drum 10, having been wound on said drum by counter-clockwise rotation of the latter, the outer drum is rotated somewhat faster than the inner drum. For example, with a rotation of 100 revolutions per minute of the inner drum, the outer drum is rotated at say 102 revolutions per minute or at a higher speed. 25 During the rotation of outer drum 12, the liquid therein is impelled by centrifugal force into cylindrical formation adjacent the inner surface of the outer drum completely therearound. It will be understood that the quantity of liquid 30 L is sufficient to provide a cylindrical layer thereof when the drum is rotated, but is below the opening 18 in the drum when the latter is stationary.

As the drums continue to rotate, the fabric or 40 other material from roll R on the inner drum 10 unwinds from the inner drum and arranges itself in the form of a winding lying adjacent the inner surface of the outer drum. In Fig. 4 of the drawings the fabric is shown partially unwound from 45 the inner drum 10 and partially wound in the outer drum 12. It will be understood that in thus unwinding from the outer drum and arranging itself in the form of a winding in the inner drum, the fabric of roll R passes through the liquid in 50 the outer drum and is subjected to the action thereof. In Fig. 5 the roll R is shown completely unwound from its core or inner drum 10 and is arranged in the form of a winding RA adjacent the inner surface of the outer drum. For the 55

sake of clearness, only a few convolutions of the windings are illustrated and the convolutions are shown spaced from each other radially of the center of the winding, but it will be understood 5 that in actual practice the convolutions of the windings on the inner and outer drums are adjacent each other.

After the fabric is completely unwound from the inner drum 10, into the form of a roll RA in 10 the outer drum, said fabric is re-wound on inner drum 10. This is accomplished by continuing the rotation of the inner and outer drums in the same direction and at the same relative speeds, that is 15 the inner and outer drums rotate in the same direction but outer drum 12 continues to rotate faster than inner drum 10. This re-winding of the material from the roll RA to the roll R on the inner drum 10 accomplished as just stated without altering the direction or relative speeds of rotation of said drums, takes place by reason of the fact that the inner end of the material of the winding is as previously stated fixed to the periphery of the inner drum. Fig. 6 of the drawings 20 illustrates the step of rewinding the material from the roll RA to the roll R on the inner drum 10, and it will be observed that the direction of winding of the material on the inner drum is at this 25 stage of the process opposite to the direction of wind of the material of roll R at the start of the process illustrated in Fig. 4.

After the material is re-wound on the inner drum 10, in the stage of the process just previously mentioned, said material is again caused to unwind from said inner drum 10 and to again arrange itself in the form of a winding RA adjacent 30 the inner surface of the outer drum 12. This is accomplished without interrupting the rotation of the inner and outer drums and without changing the direction of rotation of said drums, but by 35 now reversing the relation of the speeds of rotation of said inner and outer drums, in other words by now rotating the inner drum 10 faster than outer drum 12. Fig. 7 shows the material partially unwound from the roll R at this stage of 40 the process, that is by rotating inner drum 10 faster than outer drum 12, the different revolutions per minute between said drums being about the same as at the start of the process. Fig. 8 shows this stage of the process completed, the 45 material being completely unwound from the inner drum 10 and arranged in the form of a winding RA on the outer drum 12. Then the fabric is again rewound on the inner drum 10 by continuing 50 the rotation of said drums in the same direction, with inner drum 10 rotating faster than outer drum 12 until the material is again completely re-wound on said inner drum. At this 55 stage of the process the winding of the roll R of material on the inner drum is in the same direction as it was at the start of the process as herein described. This is illustrated in Fig. 9.

The above described steps are repeated as often as is desired or necessary for the proper treatment of the material, or as will be readily understood, in some cases it may be necessary merely to unwind the material from the inner drum and to arrange it in the form of a winding in the outer drum, or to complete only one cycle consisting of 60 unwinding the material from the inner drum, arranging it in the form of a winding in the outer drum and then rewinding the material on the inner drum.

The apparatus which will now be described and which is illustrated in Figs. 1 and 2 of the drawings is well adapted for performing the above de-

scribed method. As here shown, the outer drum 12 is carried by a sleeve or hollow shaft 20 journaled for rotation in bearings 22, said outer drum 12 being thus mounted for rotation. The inner drum 10 or core of the roll of material is mounted 5 for rotation within outer drum 12 and for that purpose is, as here shown, carried by and for rotation with a spindle or shaft 24 which extends through sleeve 20 into drum 12. Shaft 24 is mounted for rotation within and in relation to 10 sleeve 20 in any suitable manner, as for example by means of roller bearings 26 mounted within sleeve 20. Sleeve 20 has a gear 28 fixed thereto. Said gear is driven by a gear 30 fixed to a rotary shaft 32 driven in any suitable manner, as by a 15 pulley 34 operated by a belt 36 driven by a motor M.

Provision is made for rotating the inner and outer drums at different speeds, more specifically by rotating said drums so that one alternately rotates faster than the other. For this purpose shaft 24 is provided with relatively large and small gears 38 and 40, respectively, which mesh with relatively small and large gears 42 and 44, respectively, on shaft 32. A two-way clutch 46 is 25 splined to shaft 24 whereby said clutch can move longitudinally of the shaft but not circumferentially thereof, said clutch being thus rotatable with shaft 24. Gears 38 and 40, on the other hand, when disengaged from clutch 46 can move freely 30 about said shaft but are fixed longitudinally thereof. Gears 42 and 44 are fixed to shaft 32 longitudinally thereof and rotate with said shaft, and are at all times in mesh with companion gears 36 and 40, respectively. 35

Said last mentioned gears are provided with clutch engageable elements 48 and 50, respectively, for effecting rotation of said gears when engaged by said clutch. A yoked lever 52 pivoted as at 54 is provided for moving clutch 46 into engagement with gears 38 and 40 alternatively. It will be understood that when the clutch is in engagement with gear 38, shaft 24 rotates more slowly than sleeve 20 with the result that outer drum 12 rotates faster than inner drum 10. 45 When, however, it is desired to reverse this relation of speeds of rotation of said inner and outer drums, clutch 46 is disengaged from gear 38 and is engaged with gear 40, and in that case shaft 24 rotates faster than sleeve 20 and of course inner 50 drum 10 rotates faster than outer drum 12.

In accordance with the present invention, provision is made for automatically periodically reversing the relation of speeds of rotation of the inner and outer drums, or more specifically to 55 automatically rotate one drum faster than the other after a predetermined number of revolutions of said drums. A mechanism suitable for this purpose is illustrated in Fig. 1 of the drawings. As here shown, said mechanism comprises 60 a worm gear 52 fixed to and rotated by shaft 32. Said worm gear meshes with and drives a worm wheel 54. Said worm wheel is provided with a metal segment 56 connected in series with the winding W of an electro-magnet 58. More specifically, as here shown, metal segment 56, which is electrically insulated from worm wheel 54, is connected by a wire 60 to a slip ring 62 engaged by a brush 64 electrically connected to winding W. A brush 66 engages segment 56 and is connected to 70 the circuit of winding W. The armature 68 of electro-magnet 58 is carried by the arm 70 of yoked lever 52, and a spring 72 is connected to said lever arm 70. It will be understood, therefore, that when electro-magnet 58 is energized, 75

which is the case as long as brush 66 is in engagement with segment 56, armature 68 is attracted and holds clutch 46 in engagement with gear 38. When, however, after a predetermined number of revolutions of shaft 32, brush 66 is disengaged from segment 56 so that the circuit through winding W of electro-magnet 58 is interrupted, spring 72 is effective to actuate the yoked lever 52 whereby to disengage clutch 46 from gear 38 and to engage said clutch with gear 40. Thereafter as worm wheel 54 continues to rotate, brush 66 again engages segment 56 to complete the circuit through winding W of the electro-magnet 58 for attracting the armature 68 on yoked lever 52, thereby disengaging clutch 46 from gear 40 and engaging said clutch with gear 38.

As illustrated in the drawings, provision is made for supplying liquid to drum 12 and the liquid supplying device is such in accordance with the preferred form of the invention that the supply may take place during rotation of the drums. For this purpose a fluid delivery pipe 74, pivotally mounted as at 76 on a supply pipe 78, is provided. Said delivery pipe 74 has a bent portion 80 which extends through opening 18 in the front of the drum 12 to a point adjacent the inner surfaces of said drum. It will be understood that opening 18 is large enough to permit the passage of the bent portion 80 of delivery pipe 74 to said opening into and out of the drum, said delivery pipe being turned on its pivot 76 for such purposes. A pipe arrangement similar to the arrangement for supplying liquid is preferably provided for exhausting liquid from drum 12. Thus as here shown an exhaust pipe 82 similar to delivery pipe 74 is mounted on pivot 84 for turning movement about a pipe 86. Exhaust pipe 82 has a bent portion 88 which passes through opening 18 and terminates adjacent the inner surface of outer drum 12. Thus both delivery pipe 74 and exhaust pipe 82 are associated with the apparatus so that liquid may be supplied to and removed from drum 12 during the rotation thereof. Accordingly, circulation of the dye or other liquid may take place during the treatment of the material while the latter is unwound from roll R and rewound into said roll.

It will be understood that the front of the drum in which the opening 18 is provided is preferably removably secured to the front peripheral edge of outer drum 12. As here shown, said front end of the drum is provided with an observation opening 90 sealed by a glass or other transparent window 92. The front wall of drum 12 is removable to permit the insertion and removal of the fabric roll R, the inner drum 10 or core of the roll being removable from spindle or shaft 24, suitable provision being made for fixing said inner drum to said shaft so as to rotate with the latter. It will be understood that as herein described the inner drum 10 may be a member which remains permanently on the shaft 24 or may be the core of the fabric roll.

Thus it is seen that the method and apparatus hereinbefore described are well adapted to accomplish the objects of the present invention. It will be understood that while the present method and apparatus are intended primarily for use in the dyeing of fabrics, especially broad fabrics, the method and apparatus may be used for other purposes, for example for washing fabrics or other materials or for subjecting said fabrics to treatment by gases, vapors, or other fluids, the present method of winding and unwinding the fabrics being especially suitable for thus exposing successive portions of a roll of material to the

action of various fluids. It will be understood also that while I have illustrated and described the preferred form of the method and the preferred form of the apparatus, variations in both method and apparatus will occur to skilled artisans in view of the present disclosure. Therefore, I do not wish to be limited to the method and apparatus or to either of them, as herein specifically shown or described, except as may be required by the scope of the appended claims. 10

Having thus described my invention, what I claim and desire to secure by Letters Patent is:

1. Apparatus of the character described comprising a rotary outer drum adapted to contain a dye or other liquid or fluid, an inner drum, 15 mounted for rotation within said outer drum, means for rotating said drums at different speeds, respectively, and means automatically operative after a predetermined number of revolutions of one of said drums to reverse the relation of the 20 speeds of rotation of said drums.

2. Apparatus of the character described comprising a rotary outer drum adapted to contain a dye or other liquid or fluid, an inner drum 25 mounted for rotation within said outer drum concentrically thereof, said inner drum adapted to carry a roll of fabric or other material for rotation therewith, means for rotating said drums at different speeds, respectively, and means automatically operative under the control of a pre- 30 determined number of revolutions of one of said drums to reverse the relation of the speeds of rotation of said drums.

3. Apparatus of the character described comprising a rotary outer drum adapted to contain 35 a dye or other liquid or fluid, an inner drum mounted for rotation within said outer drum concentrically thereof, means for rotating said drums at different speeds, respectively, means for actuating said drum rotating means, and means 40 operative automatically during the operation of said actuating means to reverse repeatedly at regular intervals the relative speeds of rotation of said drums.

4. Apparatus of the character described comprising a rotary outer drum adapted to contain 45 a dye or other liquid or fluid, an inner drum mounted for rotation within said outer drum concentrically thereof, said inner drum adapted to carry a roll of fabric or other material for rotation therewith, means including adjustable 50 gearing for rotating said drums at different speeds, respectively, and means for adjusting said gearing automatically operative after a predetermined number of revolutions of one of said drums 55 to reverse the relation of the speeds of rotation of said drums.

5. The method of treating fabric or other material wound in a roll mounted for rotation within a drum containing a dye or other liquid or fluid, said method comprising simultaneously rotating said drum and said roll in the same direction and at such different speeds, respectively, and in such direction in relation to the direction of the winding of material of the roll that the material unwinds from said roll and arranges itself in the form of a different winding in said drum. 60

6. The method of treating fabric or other material wound in a roll mounted for rotation within a drum containing a dye or other liquid or fluid, 70 the inner end of the winding of material being secured against separation from the core of the fabric roll, said method comprising simultaneously rotating said drum and said roll in the same direction and at such different speeds, respective- 75

- ly, and in such direction in relation to the direction of the winding of the material of the roll that the material unwinds from said roll and arranges itself in the form of a different winding in said drum, and thereafter continuing said rotation of said drum and the core or drum of the material roll whereby the material previously unwound from said core is rewound thereon into a roll.
- 10 7. The method of treating fabric or other material wound in a roll mounted for rotation within a drum containing a dye or other liquid or fluid, the inner end of the winding of material being secured against separation from the core of the 15 fabric roll, said method comprising simultaneously rotating said drum and said roll in the same direction and at such different speeds, respectively, and in such direction in relation to the direction of the winding of the material of the 20 roll that the material unwinds from said roll and arranges itself in the form of a different winding in said drum, and thereafter continuing said rotation of said drum and the core or drum of the material roll so that the material previously unwound from said core is rewound thereon into a 25 roll, thereafter reversing the relation in the speeds of rotation of roll and drum without changing the direction of rotation thereof, where-

by the material again unwinds from the roll and is rewound in a different winding in said drum.

8. The method of treating fabric or other material wound in a roll mounted for rotation within a drum containing a dye or other liquid or fluid, 5 the inner end of the winding of material being secured against separation from the core of the fabric roll, said method comprising simultaneously rotating said drum and said roll in the same direction and at such different speeds, respectively, 10 and in such direction in relation to the direction of the winding of the material of the roll that the material unwinds from said roll and arranges itself in the form of a different winding in said drum, and thereafter continuing said rotation of said drum and the core or drum of the material roll so that the material previously unwound from said core is rewound thereon into a 15 roll, thereafter reversing the relation in the speeds of rotation of roll and drum without changing the direction of rotation thereof, whereby the material again unwinds from the roll and is rewound in a different winding in said drum, 20 and thereafter continuing the rotation of the core of the roll and of the drum in the same reversed speed relationship so that the material is again rewound into a roll on the core.

BERTRAM J. GOLDSMITH.
